[57] CLAIM

The ornamental design for a hat, as shown and described.

DESCRIPTION

FIG. 1 is a left, front perspective view of a hat showing my new design; and,

FIG. 2 is a right, rear perspective view thereof.

The broken line showing of the human form in FIGS. 1 and 2 is for illustrative purposes only and forms no part of the claimed design.

The word KAPTAN.KOOL appearing in FIG. 2 is a trademark.

1 Claim, 1 Drawing Sheet
